TAPE EMBOSsing MACHINE

Leonard N. Albrecht, Sausalito, and Heiko T. De Man,
Moraga, Calif., assignors to Dymo Industries, Inc.,
Berkeley, Calif., a corporation of California

Filed Oct. 11, 1962, Ser. No. 72,066

Term of patent 14 years

(Cl. D64—10)

Fig. 1.

Fig. 2.

Fig. 3.

FIGURE 1 is a top plan view of a tape embossing tool showing our new design;

FIGURE 2 is a left hand side elevational view thereof;

FIGURE 3 is a bottom plan view thereof;

FIGURE 4 is a right hand side elevational view;

FIGURE 5 is a front elevational view; and

FIGURE 6 is a rear elevational view.

The essential features of our design reside in the solid lines shown in the drawing.

We claim:

The ornamental design for a tape embossing tool, substantially as shown and described.
